Primary Examiner — Karen E Eldridge Powers

(57) **CLAIM**

The ornamental design for a makeup brush, as shown and described.

DESCRIPTION

FIG. 1 is a front elevational view of a makeup brush showing my new design;

FIG. 2 is a rear elevational view of the makeup brush shown in FIG. 1;

FIG. 3 is a perspective view of the front and bottom of the makeup brush shown in FIG. 1;

FIG. 4 is a perspective view of the rear and bottom of the makeup brush shown in FIG. 1;

FIG. 5 is a perspective view of the front and top of the makeup brush shown in FIG. 1; and,

FIG. 6 is a perspective view of the rear and top of the makeup brush shown in FIG. 1.

The broken line shown in FIGS. 3 and 4 defines the bounds of the designed design and forms no part thereof.

1 Claim, 3 Drawing Sheets
